A. Paul Spencer INVENTOR

UNITED STATES PATENT OFFICE.

A. PAUL SPENCER, OF WASHINGTON, D. C., ASSIGNOR OF TWO-THIRDS TO
JAMES C. DULIN AND JOHN T. STRATTAN, BOTH OF SAME PLACE.

DESIGN FOR A BADGE.

SPECIFICATION forming part of Design No. 15,151, dated July 15, 1884.

Application filed June 9, 1884. Term of patent 3½ years.

To all whom it may concern:

Be it known that I, A. PAUL SPENCER, a citizen of the United States, residing at Washington, in the District of Columbia, have invented a new and original Design for Campaign-Badges; and I do declare the following to be a full, clear, and exact description thereof, reference being had to the accompanying drawing, and to the letters and figures of reference marked thereon, which form a part of this specification.

The figure of the drawing represents a front or face view of the design.

This invention relates to a campaign-badge; and it consists in a design composed of two medallions or medallion-frames set side by side, adapted to receive suitable portraits. Above the medallions A, B, and arising from their point of juncture, is the representation 20 of a casque, C, surmounted by the feathers D, well known as the "Henry of Navarre" helmet. Above the medallions, and on each side

of the casque, project several flags, E. Centrally placed beneath the medallions is the representation of an eagle, F, with wings out-stretched, as shown.

What I claim is—

1. The design for a campaign-badge herein shown and described, the same consisting of the medallion-frame surmounted by the helmet and feathers, as shown.
2. The design for a campaign-badge herein shown and described, the same consisting of the medallion-frame surmounted by the helmet and feathers, and having placed centrally beneath the said frame the representation of an eagle with wings outspread, as shown.

In testimony whereof I affix my signature in presence of two witnesses.

A. PAUL SPENCER.
